UNITED STATES PATENT OFFICE.

BENJAMIN R. MULFORD, OF ORANGE, TEXAS.

AUTOMATIC CIRCUIT MAKER AND BREAKER.

1,178,535.

Specification of Letters Patent. Patented Apr. 11, 1916.

Application filed February 20, 1915. Serial No. 9,567.

To all whom it may concern:

Be it known that I, BENJAMIN R. MULFORD, a citizen of the United States, residing at Orange, in the county of Orange and 5 State of Texas, have invented certain new and useful Improvements in Automatic Circuit Makers and Breakers, of which the following is a specification.

This invention relates to new and useful 10 improvements in an automatic circuit maker and breaker.

The object of the invention is to provide a device of the character described, which will automatically and at pre-determined 15 times, make and break electrical currents through conductors and is designed to be used chiefly in connection with electric lighting systems for the purpose of turning the current on to and off from electric lights, 20 but may be used for other similar purposes, as desired.

With the above and other objects in view, the invention has particular relation to certain novel features of construction, operation and arrangement of parts, an example of which is given in this specification, and illustrated in the accompanying drawings, wherein:

Figure 1, shows an isometric view of the 30 device, as inclosed by a suitable casing. Fig. 2, shows a side elevation of the mechanism, and, Fig. 3, shows a rear view thereof, the casing in the two last mentioned figures, being shown in section. Fig. 4 is a detail view 35 of the push button switch.

Referring now more particularly to the drawings, wherein like numerals of reference designate similar parts in each of the figures: the numeral 1 designates the casing, 40 which has a clock mounted thereon. The shaft 3, has a gear connection with the clock works, but is insulated therefrom by the insulator 4, and fixed upon the rear end of the shaft 3, is the spur gear 5, which is one- 45 half the circumference of and in mesh with the spur gear 6, fixed upon the shaft 7, which in turn is rotatable in the non-conducting bearings 8, 8, carried by the supports 9, 9. The shaft 3, is geared so as to ro- 50 tate once every twelve hours, and the gear 6, and the shaft 7, will consequently perform one rotation every twenty four hours.

The spokes 10, 10, have their inner ends secured to the gear 6, and to their outer ends 55 is secured the rim 11, projecting outwardly from which is the tongue 12. Secured to

the upper ends of the supports 13, 13, and suspended between the same is the annular band 14 formed of gutta percha, or some other similar insulating material and fixed 60 to the inner side of this band are twenty-four blocks, as 15, formed of brass or some similar material and which are insulated from one another. These blocks are secured in position by means of brass rivets 16, 65 which are passed through the band 14, and secured to the respective blocks. As the gear 6, and the rim 11, carried thereby, rotate, the free end of the tongue 12, contacts with the blocks 15, successively. Upstanding from one of the bearings 8, is a stud 17, to which one end of the arm 18, is fixed and the other end of this arm carries the flexible tongue 19, which is in constant contact with the shaft 7. From the stud 17, 75 leads current conductor 20, through which the electric current is fed from the source of supply.

The numeral 21, refers to a feed conductor, which enters the casing and then separates into twenty-four parts, as 22, which lead to and are connected with each of the respective rivets 16. The ordinary punch buttons, as 23, are provided, by means of which any or all of said twenty-four conductors, may be connected with or broken from the feed conductor 21. These punch buttons are arranged in twenty-four pairs, as shown in Fig. 1, each pair controlling the corresponding conductor 22, a pair being 80 provided for each hour of the twenty-four. Normally all of the conductors 22, will be disconnected from the feed conductor and no current will pass from it to the current conductor 20. If lights, for example, are de- 85 sired for any particular hours of the twenty-four, the proper buttons 23, corresponding to said hours, may be punched, which will operate to connect the corresponding conductors 22, with the feed conductor 21, and 90 these in turn, will be connected to the corresponding blocks 15, through their corresponding rivets 16. The tongue 12, is so located that when the designated hour is reached it will contact with the correspond- 95 ing block 15, and a current will be completed through said conductor 22, said block 15, the tongue 12, the rim 11, the spoke 10, the spur gear 6, the shaft 7, the tongue, arm and stud 19, 18 and 17, respectively, to the 100 current conductor 20, all of said enumerated parts being formed of material, which will 105 110

conduct the electrical current. When the tongue 12, passes the blocks which have thus been connected with the feed conductor 21, the electrical current will be automatically broken. It is thus apparent that by punching the proper buttons, the device will be caused to complete an electrical circuit to the lights at any desired hours, and at other times the current will be broken.

10 While I have shown only one form of the device, it is obvious that mechanical changes may be made therein without departing from the principle, and I hereby reserve the right to make such structural changes, 15 as may be found practical, so long as I keep within the scope of the appended claim.

What I claim is:

1 A device of the character described including a motor having a driving shaft insulated therefrom, a spur gear on said shaft, current conductors, a fixed annular member formed of insulating material, a plurality of sections formed of conducting material, fastening means of conducting material securing said sections to the inner side of the annular member, said sections being insulated

from each other, one of said conductors being separated into parts corresponding in number to the number of said sections, said parts being in contact, one with each of said fastening means, a manual means for making and breaking the circuit through said respective parts, a mechanism driven by the motor including a driven shaft and bearings therefor, a large spur wheel on said driven shaft in mesh with said spur wheel on said driving shaft, spokes on said large spur wheel, a rim supported by said spokes and nesting within said annular member, said rim having a tongue contacting successively with said sections, a flexible tongue on one of the said bearings in contact with the driven shaft, the other current conductor being in constant contact with said flexible tongue.

45 In testimony whereof I have signed my name to this specification in the presence of two subscribing witnesses.

BENJAMIN R. MULFORD.
